Primary Examiner — Kendra Leslie Hamilton(74) Attorney, Agent, or Firm — Fogarty LLP(57) CLAIM

The ornamental design for a pet life jacket, as shown and described.

DESCRIPTION

FIG. 1 is a top, front, left perspective view of a pet life jacket, showing my new design in a first configuration; FIG. 2 is a front elevation view thereof; FIG. 3 is a rear elevation view thereof; FIG. 4 is a right-side elevation view thereof; FIG. 5 is a left-side elevation view thereof; FIG. 6 is a top plan view thereof; FIG. 7 is a bottom plan view thereof; FIG. 8 is a top plan view thereof of the pet life jacket of FIG. 1, shown flat in a second configuration; and, FIG. 9 is a bottom plan view thereof. The drawings are shaded to indicate contrasting surfaces. The broken lines showing of life jacket hardware (fasteners and clips) depict environmental subject matter only and forms no part of the claimed design. The broken lines showing on the life jacket depicts stitching and forms no part of the claimed design.
